4 Claims. (Cl. 152—356)

1

The present invention relates to an improvement in the structure of tyres for road wheels of vehicles and the like.

The behaviour of the pneumatic tyres under the work load and in their practical conditions of use has been widely studied, in view of diminishing the wear of the tyre (particularly the wear of tread), which occurs owing to the repeated deformations and the contact friction with the ground, to which the tyre is submitted.

Although the behaviour of the tyre is very complex, the main causes of wear may be considered the following two: the external friction due to the relative displacements between tread and ground, and the internal friction due to deformations. The first and the second friction cause direct and indirect damages to the structure of the tyre, by the mechanical stress directly acting and by the thermic stress indirect acting thereon, with the concomitant result of diminishing and rendering at last dangerous the resistance of the tyre.

The classic system is that of reinforcing the tyre with actual fabrics or by crossing layers of parallel filiform elements so as to allow transverse and radial deformations of the tyre impeding substantially its peripheral deformations. This system has (through a complex of elastic and non-elastic deformations of the heterogeneous system rubber-fabric) the inconvenience that the instantaneous area of contact with the ground is deformed, owing to the variation of the surface of its elemental small areas, during the time when it rests on the ground during the rotation of the wheel, with the consequence of a repeated friction causing a wear of the tread by abrasion.

Both this abrading friction with the ground, and the complex of the deformations occurring with a stress in the body of the tyre, relatively rigid and thick, determine the fatigue of the tyre and its heating, which, hardly compensated by ventilation, produces serious damages and a dangerous reduction of its resistance.

The abrading friction with the ground is reduced, according to the present invention, owing to the fact that the small areas of the contact surface between the ground and the tread remain substantially still during the time of contact in the wheel rotation, this being obtained by the structure which is described here below, with reference to the attached drawings, wherein:

Fig. 1 is a side elevation of a tyre embodied according to the present invention;

Fig. 2 is a detail perspective view of the same

2

tyre, with some parts removed in order to show the structure of the reinforcement of the tyre;

Fig. 3 is a view like that of Fig. 2, wherein a second form of embodiment of the structure of the reinforcement is shown;

Fig. 4 is a sectional view taken along the symmetry plane of the tyre, perpendicular to the axis of the said tyre;

Fig. 5 is a sectional view taken along the line V—V of Fig. 4, and corresponds with the form of embodiment shown in Fig. 2.

With reference to Figs. 1, 2, 4 and 5 of the drawings, the tyre having roughly a C-shaped cross-section, comprises on each side a bead 1 incorporating a tensile stress working ring 2, to which are connected the cords 3, forming an arc between the opposite rings along lines lying in planes passing through the axis of the tyre.

The cords 3 are incorporated in the shrunk portion 4 of the periphery of the tyre 5, and are connected between themselves by flexible but substantially inextensible elements 6, forming (particularly when the tyre contains an inflated air chamber) catenary bridges between the successive arcs of cord 3.

It is to be noted that the wordings "tensile stress working rings," "cords," and "flexible but substantially inextensible elements" are all referred to filiform or cord-shaped or band-shaped elements made of material flexible but practically inextensible under the loads which are normally applied thereon during the operation of the tyre. The material suitable to form these reinforcement elements, can be any yarn of natural or artificial textile fibres, or any thread of artificial substances (resins) or also any type and quality of metal and of metal alloy. Nevertheless, although the choice of the material suitable to each case can be made by every skilled person in the field, here below is indicated by way of non-limitative example, the following diagram of materials for the reinforcement made of rings 2, of the cords 3 and of the threads 6; steel cable for the rings 2, steel cable having a smaller cross-section for the cords 3 and cotton or polyamidic resins (nylon) cords for the yarns 6.

Instead of arranging the yarn 6 as shown in Figs. 2, 4 and 5, i. e. so as to connect, by every yarn 6, two points of two successive arcs 3 at the same distance from the ring 2 (measured along the arc 3), it is also possible, within the scope of the present invention, to place said yarns 6 as shown in Fig. 3, i. e. so that the trend of the yarns will be substantially helicoidal in re-

spect of the substantially toroidal shape of the tyre.

On the periphery of the tyre, which constructively is embodied by incorporating the elements 3 and 6 in a layer 5 having a substantially uniform thickness, which layer assumes, by vulcanization with the reinforcement, the undulated shape which is shown in the drawing (i. e. the layer 5 assumes, between the cords 3, a shape which may be called "catenary," forming outwardly projecting undulations of the peripheral surface of the tyre) are applied preferably, within the scope of the present invention, thicker portions 7 which, acting as tread, remain individually still, resting on the ground, during the rotation of the wheel, while the peripheral deformations are all substantially supported by the shrunk zones 4 of the periphery of the tyre, which zones have the maximum elasticity to fiction in the peripheral sense.

In the case of Fig. 3, the yarns 6, having helicoidal trend and forming bridges between the successive arcs 3, are preferably arranged in an even number of layers, with opposite trend, as shown in 6', in order to give the symmetry of deformation to the shrinking portions 4 of the tyre, when they are deformed during the operation. However this crossed arrangement 6' is preferable but not necessary, as layers of yarns 6, having all the same helicoidal trend, may be usefully employed.

The yarns 6 are relatively thin and numerous, and arranged so that the medium distance between two adjacent yarns is of the same order of the radius of the yarn, so that when the pneumatic tyre is inflated, there is no tendency to a hernia-like-breaking of the elastic rubber, (or equivalent elastic material) placed between two yarns and connected to each yarn by vulcanization or other equivalent system.

The structure of Fig. 3, with the crossed reinforcement 6' secured to the cords 3 has remarkable constructive advantages, as it can be embodied with an art similar to that presently followed for the common tyres; said structure has furthermore technical advantages of use, as the crossed structure 6' practically braces the tyre against the transverse stresses which, particularly when the vehicle, whereon the tyre is mounted, travels along a curve, can reach remarkable values.

According to the present invention, the tyre can be completed in its internal part (corresponding to the interval between the two beads 1 of the illustrated forms of embodiment) so as to assume the shape of a tube or of a tubular tyre, in which case, in a known way, the same tyre can act as an air-chamber. The embodiment can, then be simplified, and assume the shape shown in Figs. 1, 2, 3, 4 and 5 of the U. S. patent application 150,666 dated March 20, 1950, or the shape illustrated in Figs. 1 to 6 of Italian patent application filed at Rome on February 21, 1951, filing certificate Record No. 48, No. 428 both of "Est" Etablissement Sciences Techniques. In the two aforementioned documents, the tubular tyre is indicated as destined to operate as a track on two or more grooved wheels, while in the present invention the same tubular tyre is mounted like a common pneumatic tyre on a single grooved wheel. In this case, during the operation, the pneumatic tyre does not modify its internal radius of curvature, and practically are concerned only the external or peripheral parts of the undulations.

The greater surface offered to the air by the

tyre according to the present invention and the same undulated shape, favour ventilation and cooling of the tyre, which also owing to this reason, tends to be heated far less than the ordinary tyres.

The present invention has been described and illustrated in some preferred forms of embodiment, but it is understood that constructive variations (for instance in the shape of tread) may be brought thereto, without issuing from the scope of this invention.

I claim:

1. A tire for road wheels of vehicles comprising in combination a wall of elastic material provided along its outer surface with corrugations wherein the facing transverse surfaces of successive corrugations are spaced from each other, two beads in the inner part of said wall of elastic material for connection with the wheel, a circular substantially filiform, flexible and inextensible element in the shape of a ring embodied in each of said beads, a plurality of flexible and inextensible arc-shaped transverse cords lying in transverse planes passing through the axis of the wheel and embodied in the wall of elastic material at the inner parts of the corrugations and connected at their ends to the said rings and perpendicular to the latter, a plurality of flexible and inextensible threads crossing said transverse cords and disposed in wave form with arcuate portions connecting two-by-two the transverse cords embodied in the wall of elastic material at the inner parts of the corrugations.

2. In a tire for road wheels of vehicles, a wall of elastic material provided with two beads for connection to the wheel and with an outer surface formed with corrugations wherein the facing surfaces of two adjacent corrugations are spaced from each other, circular filiform, flexible and inextensible elements in the form of a ring embodied in the said beads, transverse flexible and inextensible cords in the form of an arc embodied in the wall of elastic material at the inner part of the corrugations, said transverse cords being connected at their ends to said rings embodied in the beads and being adapted to keep the corrugated shape of the tire in all the conditions of operation thereof, flexible and inextensible threads crossing said transverse cords and disposed in wave form with arcuate portions connecting two-by-two the transverse cords embodied in the wall of elastic material at the inner parts of the corrugations.

3. In a tubular tire for road wheels of vehicles, a wall of elastic material provided with two beads for connection to the wheel and with an outer ground contacting surface formed with corrugations wherein the facing transverse surfaces of two successive corrugations are spaced from each other, the said wall of elastic material having embodied therein a deformable structure formed with two substantially filiform, flexible and inextensible rings embodied in said beads, a plurality of transverse arc-shaped cords parallel to each other, each of the said cords connected at the ends to the said rings and embodied in the wall at the inner part of the corrugations to keep the corrugated shape of the outer surface of the wall in all the conditions of operation of the tire, a plurality of flexible and inextensible threads parallel to each other and crossing said transverse cords, said threads being waveform and having portions in the shape of arcs connecting two-by-two said transverse cords embodied in the wall at the inner part of the corrugations, the

outer surface of the elastic wall being provided with tread at the outer part of the corrugations contacting the ground.

4. In a tubular tire for road wheels of vehicles, a wall of elastic material provided with two beads for connection to the wheel and with an outer ground contacting surface formed with corrugations wherein the facing transverse surfaces of two successive corrugations are spaced from each other, the said wall of elastic material having embodied therein a deformable structure formed with two substantially filiform, flexible and inextensible rings embodied in said beads, a plurality of transverse arc-shaped cords parallel to each other, each of said cords connected at the ends to said rings and embodied in the wall at the inner part of the corrugation to keep the corrugated

shape of the outer surface of the wall in all the conditions of operation of the tire, a plurality of flexible and inextensible threads arranged in crossed layers, said layers being waveform with portions in the shape of arcs connecting two-by-two the said transverse cords embodied in the wall at the inner part of the corrugations, the outer surface of the elastic wall being provided with tread at the outer part of the corrugations contacting the ground.
